MUFFLER.

1,071,528.

Specification of Letters Patent. Patented Aug. 26, 1913.

Application filed October 28, 1912. Serial No. 728,020.

To all whom it may concern:

Be it known that I, NATHANIEL RAPP, a citizen of the United States, residing at Toledo, Lucas county, Ohio, have invented 5 new and useful Mufflers, of which the following is a specification.

This invention relates to a mechanism for receiving a discharge of fluid and dispersing said discharge in a quiet manner.

10 This invention has utility when embodied as a muffler, especially for mounting to take care of the exhaust of internal combustion engines, wherein it possesses great efficiency in minimizing any back pressure.

15 Referring to the drawings: Figure 1 is a side elevation, with a portion thereof in medial section, of an embodiment of the invention as adapted for use in connection with internal combustion engines; Fig. 2 is a 20 view thereof in side elevation with the outer housing removed; Fig. 3 is a view thereof in side elevation with the inner housing also removed; and Fig. 4 is an end view thereof with the cap removed and the lower portion 25 on the line IV of Fig. 1 looking in the direction of the arrow.

Mounted on the diaphragm 1 by the bolts 2 is the flaring core member 3 forming an enlargement or receptacle. This core member 3 tapers to the sleeve section 4 internally threaded to engage the nipple 5 which protrudes therefrom to provide a mounting for the internally threaded throat section of the core member 6 which on its opposite end, beyond the enlargement or receptacle portion thereof tapers to a second sleeve section 4 similar to the sleeve section 4 of the first core member 3. This second sleeve member 4 is connected by the externally threaded 40 nipple 5 (Fig. 3) to a second core member 6, also forming an enlargement or receptacle. The number of these enlargements may be varied as found desirable in practice. However, with the three enlargements or 45 receptacles as shown, most desirable results have been obtained when mounted to care for the exhaust of a four cylinder gasolene engine rated at from thirty to forty horsepower.

50 Mounted on the core members is an inner housing. Over the core member 3 is disposed the housing section or shell 7 having a flange 8 abutting the diaphragm 1. This

flanged section 7 has a central opening 55 slideable along the sleeve 4, and the flange 8 is normally held seated against the diaphragm 1 by three bolts 9 having nuts 10 adjustable to vary the compression of the coil springs 11. Accordingly there may be very delicate 60 adjustment of the pressure at which the shell 7 will move away from the diaphragm 1 to further compress the springs 11 and thus produce a distributed endless discharge opening about the flange 8, which will readily and automatically reseat upon relieving the pressure.

As the diaphragm 1 is fixed and the abutting section 7 is relatively movable, so about the adjacent core member 6 is the housing or shell section 12 fixed relatively to the core 70 or by being engaged between the member 6 and the end of the sleeve section 4 of the member 3. Abutting the fixed flange 13 of this fixed inner housing section 12 about the enlargement 6 is the opposing inner housing 75 section 7 with its flange 8. The inner housing sections are built up to correspond with the enlargements of the core members.

In order that the movable housing sections 7 may yield uniformly, each is shown 80 as normally held seated by three spring actuated bolts. While the first section 7 is held by the three bolts 9, the second section is held by the bolts 14 and the third section by the bolts 15.

85 For providing mounting for the first or primary housing, the diaphragm 1 is shown as having the flange 16 which is engaged by the rivets 17 to mount the outer housing section 18 provided with the ventilation openings 19 therein. The diaphragm 1 separates this spring housing portion of the device from the gas receiving end, so that there may be no heat to effect the action of the springs 11 on the several bolts 9, 14, 15. 90 This housing section 18 has a bead 20 thereon serving as a seat for the cap or end closure 21 held in position by the bolt 22 engaging the member 23 to connect with the spider 24 which is abutted by the springs 11 and 100 thus serves to keep the cap 21 seated.

105 Fitting over the flange 16 is the outer housing 25 abutting the housing section 18. This housing 25 has openings 26 therein of sufficient aggregate area to be in excess of some of the areas of the openings produced

by the movement of the flanges 8 away from their opposing seats in normal operation. The housing 25 has the bead 27 forming a seat for the cap 28 held in position by the nut 29 on the nipple 5 engaging the last core member sleeve 4, thus serving to assemble the structure as a rigid unit.

- 5 The protruding threaded nipple 5 may be connected to the exhaust of an engine, or 10 wherever it is desired to be used, and the incoming gases passing therethrough enter the first enlargement 6 to have their pressure materially reduced as they are dispersed therefrom through the openings 30 to enter the inner housing receptacle. The pressure 15 is relieved by sufficient movement of an inner housing section 7 and the passage of the gases out of the distributed endless opening along the flange 8. With this shell element 20 7 of brass or copper, or other good heat conductor, a considerable amount of heat is abstracted from the exhaust gases, in addition to that lost by the expansion in the enlargement 6 and receptacle of the inner housing 25 7, 12. The extent of the opening at flange 7 is such that in practice there is but a quiet 30 fluttering movement, and the variation of the opening size to automatically relieve the internal pressure, brings about a self cleaning, so there is no clogging accumulation in operation to bring up back pressure. Furthermore, the quick closing and great reduction of temperature by abstraction of heat from the gases and quiet expansion, effects 35 such a minimizing of back pressure as to make possible a running at less than atmospheric back pressure. Similar relief occurs in the several independently operating enlargements and receptacles so that the exhaust 40 from a gas engine is so cooled as to merely having a warming action upon one's hand, and the device operating as an effective silencer. The outer housing makes the mechanism more sightly and assists in muffling any noises. The inner housing 45 member 7 at the left in Fig. 2 is shown as slightly unseated or open.
- What is claimed and it is desired to secure by Letters Patent is:
- 50 1. A muffler comprising a receptacle provided with a gas receiving opening, a normally closed discharge opening surrounding said receptacle, and a housing for the receptacle having openings in excess of the discharge opening area.
2. A muffler comprising a receptacle provided with a gas receiving opening, a yieldably closed endless discharge opening centrally of said receptacle, and a housing for 60 the receptacle having a plurality of openings to allow escape of the discharged gas.
3. A muffler comprising a pair of members forming a chamber, one of which members is fixed and the other of which members 65 is movable adjacent the fixed member to

form a discharge opening therebetween, there being yieldable means to maintain said discharge opening normally closed, and said chamber being provided with an inlet opening opposite the fixed member.

4. A muffler embodying a pair of opposing vessel-shaped members forming a chamber therebetween, each of said members being provided with a flange, the flange of one member being yieldably seated to abut against the flange of the other to provide a normally closed discharge opening for the chamber.

5. A muffler including a pair of members forming a chamber provided with an inlet opening duct, one of said members normally seating against the other member in abutting relation and movable therefrom to provide a discharge opening therebetween, and connecting means between the members and duct for holding in assembled relation.

6. A muffler embodying a pressure distributing core having a plurality of enlargements disposed in series, and a housing for each of said enlargements.

7. A muffler having a pressure distributing core forming an enlargement, and a housing with which said core is normally in communication, said housing provided with a normally closed discharge opening.

8. A muffler comprising a pressure distributing core having a succession of enlargements in series, and a housing for each enlargement, said housings embodying opposing flanged sections relatively movable to provide discharge openings therebetween.

9. A muffler comprising a plurality of independently automatically movable sections.

10. A muffler comprising a plurality of pressure distributing receptacles each provided with a normally closed discharge opening, and each receptacle having a yieldable portion to permit opening of its discharge opening.

11. A muffler comprising a plurality of receptacles each provided with a section movable away from an adjacent section to form a discharge opening, and yieldable means normally holding said movable sections in position to maintain the discharge openings closed.

12. A muffler comprising a pair of relatively movable members forming a chamber having a discharge opening therefrom, a spring spaced from the members, and connections from the spring to the members normally to maintain the discharge opening closed.

13. A muffler comprising a receptacle provided with a gas intake opening and a normally closed outlet for said gas, and a housing for the receptacle having an escape opening for the discharged gas in excess of the discharge opening area.

14. A muffler comprising a pair of rela-

tively movable members forming a chamber having a discharge opening therefrom, a spring spaced from said chamber, a housing for said spring, and connections from the 5 spring to the members normally to maintain the discharge opening closed.

15. A muffler comprising a pair of relatively movable members forming a chamber having a normally closed discharge opening

therefrom, and adjusting means for regulating the action of said discharge opening.

In testimony whereof I affix my signature in the presence of two witnesses.
